UNITED STATES PATENT OFFICE

153,978

DESIGN FOR A TRICYCLE STEP PLATE

Chester V. Queen, Jeffersonville, Ind., assignor to
Wheelmaster Corporation, Owensboro, Ky., a
corporation of Kentucky

Application April 24, 1947, Serial No. 138,576

Term of patent 14 years

(Cl. D34—15)

To all whom it may concern:

Be it known that I, Chester V. Queen, a citizen of the United States, residing at Jeffersonville, in the county of Clark and State of Indiana, have invented a new, original, and ornamental Design for Tricycle Step Plate, of which the following is a specification, reference being had to the accompanying drawings, forming a part thereof.

Figure 1 is a side elevational view of a tricycle step plate embodying my new design, the dotted line showing the tricycle proper being for illustrative purposes only;

Figure 2 is a rear elevational view of the step plate shown in Figure 1;

Figure 3 is a sectional view taken along line 3—3 of Figure 2; and

Figure 4 is a perspective view of the step plate shown in Figure 1.

I claim:

The ornamental design for a tricycle step plate, as shown, and described.

CHESTER V. QUEEN.
